CLAIM

The ornamental design for a display screen or portion thereof with graphical user interface as shown and described.

DESCRIPTION

FIG. 1 is a front view of the first image in a sequence for a display screen or portion thereof with graphical user interface; and,

FIG. 2 is a front view of the second image in a sequence for a display screen or portion thereof with the graphical user interface.

The dot-dash broken lines illustrate the display screen or portion thereof and form no part of the claimed design. The remaining broken lines illustrate portions of the graphical user interface that form no part of the claimed design. The appearance of the graphical user interface transitions sequentially between the images shown in FIGS. 1 to 2. The process or period in which the graphical user interface transitions forms no part of the claimed design.
